Primary Examiner — Michael A. Pratt(74) *Attorney, Agent, or Firm* — Thorpe North & Western(57) **CLAIM**

The ornamental design for a projectile anchor, as shown and described.

DESCRIPTION

FIG. 1 is a perspective view of a projectile anchor in accordance with our invention;

FIG. 2 is another perspective view thereof;

FIG. 3 is a side view thereof;

FIG. 4 is a side view opposing that of FIG. 3;

FIG. 5 is another side view thereof;

FIG. 6 is a side view opposing that of FIG. 5;

FIG. 7 is a top view thereof; and,

FIG. 8 is a bottom view thereof.

The dashed lines in the drawings show environmental structure and form no part of the claimed design. Shading used in the drawings illustrates surface contours, and does not form a part of the claimed design.
